(57) **CLAIM**

We claim the ornamental design for an x-ray computed tomography scanner, as shown and described.

DESCRIPTION

FIG. 1 is a front perspective view of an x-ray computed tomography scanner in accordance with the present design.

FIG. 2 is a front view of an x-ray computed tomography scanner in accordance with the present design.

FIG. 3 is a right side view of an x-ray computed tomography scanner in accordance with the present design.

FIG. 4 is a left side view of an x-ray computed tomography scanner in accordance with the present design.

FIG. 5 is a back view of an x-ray computed tomography scanner in accordance with the present design. The dot-dash line forms the boundary of the claim and forms no part thereof; and,

FIG. 6 is a top view of an x-ray computed tomography scanner in accordance with the present design.

The broken lines represent portions of the x-ray computed tomography scanner that form no part of the claimed design.

1 Claim, 6 Drawing Sheets
